ELGAN SAMUEL SLOAN, OF SHIPPENVILLE, PENNSYLVANIA.

PUMPING POWER.

Application filed May 3, 1922. Serial No. 558,323.

To all whom it may concern:

Be it known that I, ELGAN SAMUEL SLOAN, a citizen of the United States, and a resident of Shippenville, in the county of Clarion and State of Pennsylvania, have invented certain new and useful Improvements in Pumping Powers, of which the following is a specification.

This invention relates to power transmitting devices and more particularly to what is known in the oil well art as pumping powers.

In the pumping powers now in use, the main shaft is comparatively short and consequently, the great strain incident to the operation of the apparatus in hilly countries and where the work is not always at right angles to the shaft greatly decreases the life of the bearings and the associated parts of the apparatus.

It is therefore an important object of this invention to provide a pumping power which employs an extremely heavy base into which is rotatably extended the main shaft and it is desirable to have the main shaft somewhat long and surrounded by a suitable number of relatively stationary bearings so that the leverage cannot exert an excessive friction and thereby decrease the life of the bearings.

One of the principal features of this invention resides in providing novel and reliable means whereby the oil which is conveyed to the main bevel gear may be returned to the small oil receiver which supplies the power transmitting pinion with lubricant.

Also, the invention aims to provide a pumping power wherein the lubricant carried thereby and the moisture in the lubricant may be drained off as the occasion requires.

Also, a further object is to provide simple and reliable means whereby the oil surrounding the main shaft may be withdrawn for the purpose of replacement.

Other objects and advantages will be apparent during the course of the following description.

In the accompanying drawings, forming a part of this application and in which like numerals are employed to designate like parts throughout the same,

Fig. 1 is a vertical sectional view through the improved power transmitting apparatus,

Fig. 2 is a plan view thereof, parts being broken away,

Fig. 3 is a horizontal sectional view taken on the line 3—3 of Fig. 1, and

Fig. 4 is a sectional view through one of the bearings embodied in the invention.

In the drawings, wherein for the purpose of illustration is shown a preferred embodiment of the invention, the numeral 5 designates a bed preferably formed from concrete and being of sufficient size and strength to withstand the strain incident to the use of the apparatus. The concrete bed or foundation 5 is preferably reinforced as indicated at 6.

In carrying out the invention, a drive shaft 8 is mounted upon the top of the bed 5 and is rotatably extended through a pair of aligned cap bearings 9 and between the cap bearings I have provided a pinion 10 which meshes with a main gear 11. As illustrated in Fig. 1, the main gear 11 is beveled and is keyed upon a main vertically arranged shaft 12 to which upper and lower eccentrics 13 and 14 are connected. The eccentrics 13 and 14 have connection with a suitable number of well pumps and when the main shaft 12 is rotated the reciprocating members of the pumps will of course be operated, all of which is old and well known in the art.

The main shaft 12 is extended downwardly into a socket in the bed 5 and is rotatably passed through upper and lower bearings 16 and 19 respectively, the upper bearing 16 being carried by a casting or metal frame 18. The upper bearing 16 is as illustrated in Fig. 4, provided with longitudinally extending internal grooves 20 through which the oil may flow for maintaining the main shaft in a well lubricated condition. The upper side of the frame or casting 18 is cupped as indicated at 21 for the reception of oil which flows through the upper bearing by means of the oppositely arranged grooves 20.

The upper bearing 16 is supported by the shoulder 23 formed on the upper portion of a tubular member 24 which constitutes the reservoir for the reception of a quantity of oil.

The lower portion of the main shaft 12 is somewhat reduced, as indicated at 26, and is extended through the lower bearing 19 which is carried by a casting or frame 27

having a base 28. The base 28 of the casting or frame 27 contacts with the lower end of the tubular member 24 and thereby closes the lower end of the tubular member to prevent the escape of oil. It might be stated that the bearing 19 and the base 28 of the casting 27 form a socket to rotatably receive the reduced lower end of the main shaft 12 and thrust plates 30 of a suitable thickness are arranged between the base plate 28 and the lower end of the main shaft. The thrust plates 30 may be renewed as the same wear and in this manner the vertical shaft 12 may at all times be maintained in its proper position.

Furthermore, the thrust plates 30 may be provided with centrally arranged openings to align with the centrally arranged opening or passage 33 in the base 28 so that oil from the main reservoir may enter the inlet member 34 of a pump 35. The pump 35 extends out through the upper side of the bed 5 and forms a convenient means whereby the oil may be withdrawn from the main reservoir. It is understood, of course, that oil may be supplied to the main reservoir defined by the tubular member 24 through the cup 21.

In carrying out the invention, the apparatus, and more particularly the concrete bed of the same, may be strengthened and reinforced by bars 40 threaded as indicated at 41 into the frame or casting 18. One of the bars 40 is threaded into a lateral projection 42 of the casting 18 and it is upon this projection 42 that one of the cap bearings 9 is mounted.

Attention is directed to the fact that the top of the bed 5 is provided directly beneath the bevel gear 11 with an annular groove 60 which is inclined downwardly toward the oil receiver 61 directly beneath the pinion 10. That is to say, the annular groove 60 is of an increased depth directly beneath the pinion 10 so that the pinion 10 will at all times operate in oil. The oil picked up by the pinion 10 and supplied to the teeth of the bevel gear 11 is dropped into the annular trough or groove 60 and flows back into the receiver 61.

The oil may be drained from the receiver 61 at any time by means of a drain pipe 63 which, as illustrated in Fig. 3, is provided with a control valve 64.

In operation, it will be apparent that a power transmitting device apparatus constructed in accordance with this invention is possessed of the strength necessary to withstand the strains incident to use and particularly the bearings 16 and 19 are not rapidly worn by the strain on the main shaft 12.

Frequently when operating in hilly country or when the pull is not at right angles to the eccentrics, the strain on the main shaft causes the bearings to get out of alignment and the bearings are soon worn

and become unfit for further use. However, in the use of this invention, the rapid wearing of the bearings is overcome and the unusual length of the main shaft 12 and the strength of the bed hold the shaft properly in position and eliminates excessive vibration.

Also, an adequate supply of oil is maintained through all the moving parts at all times which contributes greatly to the wearing qualities of the apparatus.

Having thus described the invention, what is claimed is:—

1. An apparatus of the character specified comprising a bed, upper and lower bearings arranged in the bed, frames receiving said bearings and embedded in said bed, a main shaft extending into the bed and terminating adjacent the bottom of the same, the upper end of the main shaft being extended above the top of the bed, power transmitting devices arranged on the upper end of said main shaft, a tubular member surrounding said main shaft and having connection with said upper and lower frames and constituting a lubricant-receiving reservoir, a pump connected to the lower frame for withdrawing the oil from the oil reservoir, and thrust plates arranged between the lower end of said main shaft and the lower frame and having oil passages establishing communication between the oil reservoir and said pump.

2. An apparatus of the character specified comprising a bed, upper and lower bearings arranged in the bed, frames receiving said bearings and embedded in said bed, a main shaft extending into the bed and terminating adjacent the bottom of the same, the upper end of the main shaft being extended above the top of the bed, power transmitting devices arranged on the upper end of said main shaft, a tubular member surrounding said main shaft and having connection with said upper and lower frames and constituting a lubricant-receiving reservoir, a pump connected to the lower frame for withdrawing the oil from the oil reservoir, and thrust plates arranged between the lower end of said main shaft and the lower frame and having oil passages establishing communication between the oil reservoir and said pump, the upper frame being provided with an oil cup forming a means for supplying the upper bearing with oil.

3. An apparatus of the character specified comprising a bed, upper and lower bearings arranged in the bed, frames receiving said bearings and embedded in said bed, a main shaft extending into the bed and terminating adjacent the bottom of the same, the upper end of the main shaft being extended above the top of the bed, power transmitting devices arranged on the upper end of said main shaft, a tubular member surrounding

said main shaft and having connection with said upper and lower frames and constituting a lubricant-receiving reservoir, means connected to the lower frame for withdrawing the oil from the oil reservoir, thrust plates arranged between the lower end of said main shaft and the lower frame and having oil passages establishing communication between the oil reservoir and said means, the upper frame being provided with an oil cup forming a means for supplying the upper bearing with oil, and a drive shaft having connection with said main shaft.

4. An apparatus of the character specified comprising a bed, upper and lower bearings arranged in the bed, frames receiving said bearings and embedded in said bed, a main shaft extending through the bearings, the upper end of the main shaft being extended above the top of the bed, power transmitting devices arranged on the upper end of said main shaft, a tubular member surrounding said main shaft and having connection with said upper and lower frames and constituting a lubricant-receiving reservoir, means connected to the lower frame for withdrawing the oil from the oil reservoir, thrust plates arranged between the lower end of said main shaft and the lower frame and having oil passages establishing communication between the oil reservoir and said pump, one of said frames being provided with an oil cup forming a means for supplying the upper bearing with oil, a drive shaft extending at right angles to said main shaft, bearings rotatably connecting said drive shaft to said bed, a pinion mounted on said drive shaft between said last named bearings, a gear keyed to said main shaft and engaging said pinion, the top of said bed being provided with an annular trough gradually increased in depth toward one side of the bed, the bed directly beneath said pinion being formed with an oil receiver in communication with said trough.

5. An apparatus of the character specified comprising a bed, upper and lower bearings arranged in the bed, frames receiving said bearings and embedded in said bed, a main shaft extending into the bed and terminating adjacent the bottom of the same, the upper end of the main shaft being extended above the top of the bed, power transmitting devices arranged on the upper end of said main shaft, a tubular member surrounding said main shaft and having connection with said upper and lower frames and constituting a lubricant-receiving reservoir, a pump connected to the lower frame for withdrawing the oil from the oil reservoir, thrust plates arranged between the lower end of said main shaft and the lower frame and having oil passages establishing communication between the oil reservoir and said pump, one of said frames being provided with an oil cup forming a means for supplying the upper bearing with oil, a drive shaft extending at right angles to said main shaft, bearings rotatably connecting said drive shaft to said bed, a pinion mounted on said drive shaft

between said last named bearings, and a gear leading to said main shaft and engaging said pinion, the top of said bed being provided with an annular trough gradually increased in depth toward one side of the bed.

6. An apparatus of the character specified comprising a bed, upper and lower bearings arranged in the bed, frames receiving said bearings and embedded in said bed, a main shaft extending into the bed and terminating adjacent the bottom of the same, the upper end of the main shaft being extended above the top of the bed, power transmitting devices arranged on the upper end of said main shaft, a tubular member surrounding said main shaft and having connection with said upper and lower frames and constituting a lubricant-receiving reservoir, a pump connected to the lower frame for withdrawing the oil from the oil reservoir, thrust plates arranged between the lower end of said main shaft and the lower frame and having oil passages establishing communication between the oil reservoir and said pump, one of said frames being provided with an oil cup forming a means for supplying the upper bearing with oil, a drive shaft extending at right angles to said main shaft, bearings rotatably connecting said drive shaft to said bed, a pinion mounted on said drive shaft between said last named bearings, a gear keyed to said main shaft and engaging said pinion, the top of said bed being provided with an annular trough gradually increased in depth toward one side of the bed, the bed directly beneath said pinion being formed with an oil receiver in communication with said trough.

7. An apparatus of the character specified comprising a bed, upper and lower bearings arranged in the bed, frames receiving said bearings and embedded in said bed, a main shaft extending into the bed and terminating adjacent the bottom of the same, the upper end of the main shaft being extended above the top of the bed, power transmitting devices arranged on the upper end of said main shaft, a tubular member surrounding said main shaft and having connection with said upper and lower frames and constituting a lubricant-receiving reservoir, a pump connected to the lower frame for withdrawing the oil from the oil reservoir, thrust plates arranged between the lower end of said main shaft and the lower frame and having oil passages establishing communication between the oil reservoir and said pump, frames being provided with an oil cup forming a means for supplying the upper bearing with oil, a drive shaft extending at right angles to said main shaft, bearings rotatably connecting said drive shaft to said bed, a pinion mounted on said drive shaft between said last named bearings, a gear leading to said main shaft and engaging said pinion, the top of said bed being provided with an annular

trough gradually increased in depth toward one side of the bed, the bed directly beneath said pinion being formed with an oil receiver in communication with said trough, and reinforcing means for said frames.

8. An apparatus of the character specified comprising a bed, upper and lower frames embedded in the bed, a tubular member receiving the major portion of the lower frame and having connection with the upper frame, said tubular member constituting a main oil reservoir, upper and lower bearings carried by said frames, a main shaft extending through said bearings, said lower frame be-

ing provided with a base engaging the lower end of said tubular member and closing the same, the top of said upper frame being provided with a recess defining an oil cup, cap bearings carried by said bed and said upper frame, a drive shaft extending at right angles to said main shaft and rotatably supported by said cap bearings, a pinion mounted on said drive shaft between said cap bearings, and a bevel gear keyed on said main shaft and having connection with said pinion.

ELGAN SAMUEL SLOAN.
